W. H. WHARTON

REVERSING VALVE FOR OPEN HEARTH AND OTHER TYPES OF REGENERATIVE FURNACES

Filed Jan. 14, 1921

- Inventor -
William Henry Wharton.

UNITED STATES PATENT OFFICE.

WILLIAM HENRY WHARTON, OF TORONTO, ONTARIO, CANADA.

REVERSING VALVE FOR OPEN-HEARTH AND OTHER TYPES OF REGENERATIVE FURNACES.

Application filed January 14, 1921. Serial No. 437,262.

To all whom it may concern:

Be it known that I, WILLIAM HENRY WHARTON, a citizen of the Dominion of Canada, residing at 37 Bloor Street East, 5 Toronto, in the county of York and Province of Ontario, Canada, have invented certain new and useful Improvements in Reversing Valves for Open-Hearth and Other Types of Regenerative Furnaces, of which 10 the following is a specification.

My invention relates to improvements in reversing valves for open hearth and other types of regenerative furnaces which while being capable of being used as gas valves are 15 primarily intended to be used for air, and the object of the invention is to devise a reversing valve system in which a positively regulated amount of air can be supplied to the furnace under suitable pressure.

20 A further object is to devise means for changing the direction of the air supplied from one regenerative chamber to the other with a simultaneous change in direction of exit of the hot waste gases.

25 A still further object is to provide means for raising the temperature of the air fed into the respective regenerative chambers, through the medium of the hot waste gases, while such air at the same time acts as a 30 cooling medium for the valve through which it passes.

Another object is to devise means for 35 withdrawing the respective valves from contact with the hot waste gases which are passing from the furnace to the stack.

My invention consists of a reversing valve system constructed and arranged all as hereinafter more particularly described and 40 illustrated in the accompanying drawing in which:

Fig. 1 is a plan of the complete valve mechanism one-half of the plan being shown in horizontal section, the whole plan being symmetrical about the centre line.

45 Fig. 2 is an elevation of same with a portion of the air chamber cover removed, showing the inside of the air chamber and the air regulating mechanism contained therein.

50 Fig. 3 is an end elevation of one of the valves with a section through the air chamber.

Fig. 4 is an elevational view of one of the valve seats, taken from the stack side, and

Fig. 5 is a vertical longitudinal section 55 through one of the cylinders W and attached cylinder X.

Like characters of reference indicate corresponding parts in the different views.

A is the reversing valve chamber composed of any suitable material and preferably bricklined as to walls and roof. B and C are flues leading in opposite directions from the chamber A to the respective regenerative chambers (not shown) situated one 60 at each end of the furnace. D is a flue leading from the chamber A to the chimney stack.

E is a vertical partition extending forwardly from the rear wall of the chamber A and separating the flues B and C, said partition E at its forward end connecting with the transversely extending aligned partitions F and G. While the partition E 70 may be composed of a combination of brick work and steel or cast iron plates, the partitions F and G are hollow and are adapted to be filled with water by being connected to the water circulation system hereinafter described.

Each of the partitions F and G has a valve seat orifice 9 extending therethrough in which a centrally positioned hollow boss J is located, supported by the radially extending bowed tubular arms H communicating with the respective partitions F and G. Thus the water in the partitions is permitted to fill the arms H and the hollow boss J. M is a water discharge pipe from each 80 hollow partition F and G.

I will now describe the construction of the valves which are used in connection with the valve seat orifices 9 in the partitions F and G. As both valves and the means for actuating them are identical in construction the description of one will suffice for both.

Each boss J supports the forward end of the hollow shaft K which communicates with the interior of the boss, said shaft constituting a valve stem upon which is slidably mounted the hollow valve N of substantially mushroom shape. The valve is so designed as to impede as little as possible the air introduced therethrough, while at the same time offering the maximum surface possible to its cooling influence.

A rearwardly directed air discharge port 10 is provided in each valve N. Extending

rearwardly from each valve N is a tube O which is slidably supported at its rear end on the webs 11 of the air chamber P. The tube O is connected to the forward end of 5 the hollow piston rod Q which extends around the shaft K and has its rear end mounted in the piston R reciprocable in the cylinder W. Connected air regulating cones S and T positioned in spaced relation to 10 each other are slidably mounted in the air chamber P into which air is pumped under pressure, the forward cone S having a central orifice 12 therethrough and the cone T having a rearwardly extending skirt 13, 15 said cones being of such diameter as to permit the tube O to slide thereover and to engage the shoulder 14 on such skirt. Steam or compressed air is introduced into the respective ends of the cylinder W through either of the spaced apart pipes 1 or 2 which are connected thereto intermediately of the length of such cylinders, each pair of pipes 1 and 2 leading preferably to a threeway valve (not shown). The pipes 1 and 2 have 20 branch pipes 3 and 4 respectively, with retarding valves 5 and 6 therein, and connected to the rear and forward ends of each cylinder W.

Below each cylinder W is a small cylinder 30 X communicating therewith through the bypass 7. U is a piston reciprocable in the small cylinder X. V is a forwardly extending threaded piston rod connected to the piston U at its rear end and at its forward 35 end to the skirt of the cone T. Y is a wheel screwed on the piston rod V and capable of longitudinal adjustment thereon to act as a stop to limit the movement of the piston rod.

40 K¹ is a pipe connected to the rear end of each hollow shaft K and extending through the piston rod Q, the piston R, and cylinder W, the rear end of the pipes K¹ being connected to the water supply pipe 8. Thus the respective valve seats and partitions F and G are cooled by water which is circulated from the supply pipe 8, through the pipe K¹, the hollow shafts or valve stems K, 45 bosses J, arms H, to the partitions F and G, from whence it is discharged through the discharge pipes M.

The operation of my reversing valve is as follows:

50 Referring to Fig. 1 it will be seen that the left hand valve N is in the seated position and that air under pressure is being introduced, from the corresponding air chamber P, through and in front of the cone S, through the tube O and valve N out 55 of the annular port 10, into the flue B and thence into its connected regenerative chamber. Such air is heated by the hot waste gases from the furnace on the stack side of the partition F striking the front face 60 of the closed valve N, such valve face being

correspondingly cooled by such air as it is deflected from the tube O around such surface and out of the port 10.

The other valve N is in the open position wherein it is withdrawn into the recess 15 70 in the rear wall of the valve chamber A, thus being out of the path of the hot waste gases being discharged from the furnace through the flue C, valve seat orifice 9, the partition G, into the forward portion of 75 the valve chamber A and finally out of the flue D into the stack.

Now assuming that conditions in the furnace require the reversing of the valves, I will describe the operation of the mechanism 80 for closing the open valve N and opening its fellow. Steam or air under pressure is admitted to opposite ends of the two cylinders W, at the rear of the right cylinder and at the forward end of the left hand one, thus causing the right hand piston R and attached piston rod Q to be pushed forwardly and with it the right hand valve N, until it is in the seated position on the valve seat 9 of the partition G, consequently permitting the attached tube O to uncover the inlet from the corresponding air chamber P and admit a supply of air from such chamber P through the tube O into such valve N and thence into the flue C, the amount of air 95 depending on the adjustment of the cones S and T, while the left hand piston R and piston rod Q with the attached valve N are moved rearwardly under the influence of the steam or air pressure introduced into the forward end of the left hand cylinder W, until the tube O covers the inlet from the air chamber P, its rear end engaging the shoulder 14 on the skirt 13 of the cone T, thus cutting off the air supply simultaneously with the unseating of the left hand valve N. When this is done the hot waste gases from the furnace are now discharged through the flue B, through the valve seat orifice 9 in the partition F into the forward 100 portion of the valve chamber A and thence to the stack through the flue D.

In admitting air or steam pressure to the respective cylinders W the elastic fluid admitted through the pipe 2 will flow through the pipe 3, the retarding valve 5 not obstructing its flow in this direction, into the cylinder W forcing the piston R forwardly. As the inlet of the pipe 2 is uncovered by the piston moving forwardly, the elastic fluid will also flow in through this pipe. The steam or air being exhausted will be forced out of the cylinder W by the pipe 1 until the opening of such pipe into the cylinder is covered by the piston, when it will be exhausted through the branch pipe 4, through the retarding valve 6, which impedes its flow and causes such fluid in the forward end of the cylinder W to cushion the piston R as it completes its forward 115 120 125 130

stroke. Similarly when the working fluid is admitted through the pipe 1 to the forward end of the cylinder the exhaust will be through the pipe 2 and then through the 5 pipe 3, the retarding valve 5 impeding the flow in this case and cushioning the piston on its rearward stroke.

As the piston R moves forwardly from its rearmost position it uncovers the opening 10 of the by-pass 7 in the cylinder W, and thus the fluid passing through the by-pass 7 into the small cylinder X forces the piston U forwardly. The piston rod V pushes forwardly the two cones S and T to the required position as determined by the setting 15 of the adjustment wheel Y. The wheel Y acts as a stop for the piston rod V and limits the forward movement of the cones S and T depending on its adjustment, thus varying 20 the distance of the cone S from the rear end of the tube O, consequently regulating the volume of air admitted from the air chamber P to the tube O and thence to the chamber B or C depending upon which valve is 25 operating. It is obvious that if, by adjusting the wheel Y so that the piston V is allowed its maximum throw the cone S will be permitted to move forwardly until it practically closes the aperture between it 30 and the interior of the tube O when the air under pressure will then only be admitted through the interior orifice in the cone.

Consequently it will be apparent that as either valve N is moved forwardly onto its 35 seat wherein the tube O uncovers the inlet from the air chamber P, the cones S and T will be moved forwardly to regulate the admission of air to the tube O. The reverse of these different operations is mean- 40 while taking place in the other valve mechanism.

The purpose of regulating the supply of air is to make for more perfect combustion of the combustible gases, and also to compensate for variations in atmospheric pressure or the pressure of the combustible gases, as well as to enable the operator to maintain oxidizing or neutral conditions in the furnace as required.

50 I claim:

1. In reversing valves for open hearth and other type regenerative furnaces, the combination with a valve chamber divided into three compartments, flues communicating with the respective compartments, vertically positioned water-cooled hollow partitions between two compartments and the third compartment having openings therethrough constituting vertically positioned water-cooled valve seats, and valve bodies alternately closing the openings in the respective partitions.

60 2. In reversing valves for open hearth and other type regenerative furnaces, the combination with a valve chamber divided

into three compartments, flues communicating with the respective compartments, vertically positioned water-cooled hollow partitions between two compartments and the third compartment having openings therethrough constituting vertically positioned water-cooled valve seats, and air cooled valve bodies alternately closing the openings in the respective partitions. 70

3. In reversing valves for open hearth and other type regenerative furnaces, the combination with a valve chamber divided into three compartments, flues communicating with the respective compartments, water-cooled partitions between two compartments and the third compartment having openings therethrough constituting water-cooled valve seats, means for introducing air alternately to the flues through the two compartments of the valve chamber through the 80 valve bodies upon the latter being in their seated position, said means cutting off the admission of the air upon the valve bodies being moved out of engagement with their seats. 90

4. In reversing valves for open hearth and other type regenerative furnaces, the combination with a valve chamber divided into three compartments, flues communicating with the respective compartments, water-cooled partitions between two compartments and the third compartment having openings therethrough constituting water-cooled valve seats, means for introducing air alternately to the flues in the 100 two portions of the valve chamber through the valve bodies upon the latter being in their seated position, means regulating the supply of air admitted to the flues through the valve bodies, and means for cutting off the admission of the air upon the valve bodies being moved out of engagement with their seats. 105

5. In reversing valves for open hearth and other type regenerative furnaces, the combination with the respective regenerative chambers of the furnace, and the stack, of a valve chamber, partitions dividing the valve chamber into three distinct compartments, a flue connecting one compartment with the stack, flues connecting the other two compartments with the respective regenerative chambers, the partitions between the regenerative chamber flue connected compartments and the stack flue connected compartment having openings therethrough, constituting valve seats, valves for closing said openings, means for alternately admitting air to one of the regenerative chamber flue connected compartments and thence through the flue to the corresponding regenerative chamber upon the valve in the compartment being seated, the waste gases from the other regenerative chamber being 125 expelled through the other compartment 130

- 4 and open valve into the stack flue connected compartment.
6. In reversing valves for open hearth and other type regenerative furnaces, the combination of the respective regenerative chambers of the furnace, and the stack, of a valve chamber, partitions dividing the valve chamber into three distinct compartments, a flue connecting one compartment with the stack, flues connecting the other two compartments with the respective regenerative chambers, the partitions between the regenerative chamber flue connected compartments and the stack flue connected compartments having openings therethrough constituting valve seats, valves for closing said openings, means for alternately admitting air to one of the regenerative chamber flue connected compartments and thence through the flue 70 to the corresponding regenerative chamber upon the valve in the compartment being seated, the waste gases from the other regenerative chamber being expelled through the other compartment and open valve into the stack flue connected compartment, said valves slidably rearwardly into flame protecting recesses in the rear walls of the compartments. 75
9. In reversing valves for open hearth and other type regenerative furnaces, the combination with the valve chamber regenerative chambers, stack and flues from the regenerative chambers to the valve chamber, of valves for providing communication between the stack and the alternate regenerative chamber communicating flues, and means for admitting air to each of the flues upon the particular valve being closed, said means cutting off the supply of air when the valve is 80 open. 85
10. In reversing valves for open hearth and other type regenerative furnaces, the combination with the valve chamber, regenerative chambers, stack and flues from the regenerative chambers to the valve chamber, of valves for providing communication between the stack and the alternate regenerative chamber communicating flues, means for admitting air to alternate flues upon the particular valve being closed, and adjustable means for varying the volume of the air admitted prior to its admission to the valves. 90 95 100
11. In reversing valves for open hearth and other type regenerative furnaces, the combination with the valve chamber, regenerative chambers, stack and flues from the regenerative chambers to the valve chamber, of valves for providing communication between the stack and the alternate regenerative chamber communicating flues, means for admitting air through the valves to each of the flues upon the particular valve being closed, said means cutting off the supply of air when the valve is open. 105 110 115
12. In reversing valves for open hearth and other type regenerative furnaces, the combination with the valve chamber, regenerative chambers, stack and flues from the regenerative chambers to the valve chamber, of valves for providing communication between the stack and the alternate regenerative chamber communicating flues, and means for admitting air through the valves to alternate flues upon the particular valve being closed, and adjustable means for varying the volume of the air admitted. 120 125
13. In reversing valves for open hearth and other type regenerative furnaces, the

combination with the valve chambers and the regenerative chamber flues, of means for admitting air to alternate flues through the reversing valves, said supply of air being 5 automatically cut off upon the opening of the valves.

14. In reversing valves for open hearth and other type regenerative furnaces, the combination with the valve chambers and 10 the regenerative chamber flues, of means for admitting air to alternate flues through the reversing valves, said supply of air being automatically cut off upon the opening of the valves, and means for regulating the 15 volume of air so admitted.

15. In reversing valves for open hearth and other type regenerative furnaces, the combination with the valve chambers and the regenerative chamber flues, of means for 20 admitting air to alternate flues through the reversing valves, said supply of air being automatically cut off upon the opening of the valves, and means for regulating the volume of air so admitted, said regulating 25 means moved into the inoperative and operative positions respectively on the opening and closing of the valves.

16. In reversing valves for open hearth and other type regenerative furnaces the 30 combination with the regenerator, of a plurality of valves, each comprising a seat, a hollow valve body having an air outlet and means for conducting the entire volume of air through the hollow valve body to the regenerator.

17. In reversing valves for open hearth and other type regenerative furnaces the combination with the regenerator, of a plurality of valves, each comprising a seat, a 40 hollow valve body having a rearwardly facing air outlet, and means for conducting the entire volume of air into the hollow valve body to the regenerator.

18. In reversing valves for open hearth and other type regenerative furnaces, a plurality of valves, each comprising a seat, a hollow valve body having a rearwardly facing air outlet, means for conducting air into the hollow valve body and means for cutting 50 off the air supply upon the valve body being off its seat.

19. In reversing valves for open hearth and other type regenerative furnaces, a plurality of valves, each comprising a seat, a hollow valve body having a rearwardly facing air outlet, means for conducting air into the hollow valve body, means for cutting off the air supply upon the valve body being off its seat and means for regulating the 60 volume of air admitted to the valve body.

20. In reversing valves for open hearth and other type regenerative furnaces, a plurality of valves, each comprising a seat, a hollow valve body having a rearwardly facing air outlet, means for conducting air into 65

the hollow valve body, means for cutting off the air supply upon the valve body being off its seat and means for regulating the volume of air admitted to the valve body, said regulating means thrown into the functioning position upon the valve being seated. 70

21. In reversing valves for open hearth and other type regenerative furnaces the combination with the regenerator, of a plurality of valves, each comprising a seat, a hollow valve body having an air outlet, means for conducting the entire volume of air through the hollow valve body to the regenerator and means for water-cooling the valve seat. 75

22. In reversing valves for open hearth and other type regenerative furnaces, a plurality of valves, each comprising a seat, a hollow valve body having an air outlet, means for conducting air through the hollow valve body, means for water-cooling the valve seat and means for introducing the cooling water into the hollow valve seat 80 through the valve body. 85

23. In reversing valves for open hearth and other type regenerative furnaces, opposingly operable valves, each comprising a hollow water-cooled seat portion constituting a partition having an orifice therethrough, a valve compartment, a hollow valve supporting shaft extending longitudinally through the valve chambers, said valve supporting shaft communicating with the hollow seat portion, means for circulating water through the hollow shaft and seat, a valve body slidable on the hollow shaft and means for operating the valve body into its open and closed positions. 90

24. In reversing valves for open hearth and other type regenerative furnaces, opposingly operable valves, each comprising a valve seat constituting a partition having an orifice therethrough, a valve receiving compartment, an air chamber communicating with the valve receiving compartment, a valve supporting shaft extending longitudinally of the valve compartment and air chamber, a hollow valve body having a rearwardly extending tubular portion and slideable on the shaft, said valve body having an air outlet aperture therein, means for operating the valve body into the open and closed positions, said tubular portion cutting off the admission of air from the air chamber to the valve receiving compartment upon the valve being moved off its seat. 105

25. In reversing valves for open hearth and other type regenerative furnaces, opposingly operable valves, each comprising a valve seat constituting a partition having an orifice therethrough, a valve receiving compartment, an air chamber communicating with the valve receiving compartment, a valve supporting shaft extending longitudinally of the valve compartment and air chamber, a 110

hollow valve body having a rearwardly extending tubular portion and slideable on the shaft, said valve body having air outlet apertures therein, means for operating the 5 valve body into the open and closed positions, said tubular portion cutting off the admission of air from the air chamber to the valve receiving compartment upon the valve being moved off its seat and means for 10 regulating the volume of air admitted through the tubular portion and valve body to the valve receiving compartment.

26. In reversing valves for open hearth and other type regenerative furnaces, opposingly operable valves, each comprising a 15 valve seat constituting a partition having an orifice therethrough, a valve receiving compartment, an air chamber communicating with the valve receiving compartment, a valve supporting shaft extending longitudinally of the valve compartment and air chamber, a hollow valve body having a rearwardly extending tubular portion and slideable on the shaft, said valve body having 20 air outlet apertures therein, means for operating the valve body into the open and closed positions, said tubular portion cutting off the admission of air from the air chamber to the valve receiving compartment upon the valve being moved off its seat, a plurality of suitably spaced apart air regulating cones slidably mounted with 25 respect to the valve shaft, the forward cone having a central aperture therethrough and means for operating the cones into the functioning position simultaneously with the closing of each valve.

27. In reversing valves for open hearth and other type regenerative furnaces, opposingly operable valves, each comprising a 30 valve seat constituting a partition having an orifice therethrough, a valve receiving compartment, an air chamber communicating with the valve receiving compartment, a valve supporting shaft extending longitudinally of the valve compartment and air chamber, a hollow valve body having a rear- 35

wardly extending tubular portion and slideable on the shaft, said valve body having air outlet apertures therein, means for operating the valve body into the open and closed positions, said tubular portion cutting off the admission of air from the air chamber to the valve receiving compartment upon the valve being moved off its seat, a plurality of suitably spaced apart air regulating cones slidably mounted with respect to the valve shaft, the forward cone having a central aperture therethrough and means for operating the cones into the functioning position simultaneously with the closing of each valve, the tubular portion of the valve body moving the cones into their non-functioning position on the opening of the valves. 60

28. In reversing valves for open hearth and other type regenerative furnaces, opposingly operable valves, each comprising a valve seat constituting a partition having an orifice therethrough, a valve receiving 70 compartment, an air chamber communicating with the valve receiving compartment, a valve supporting shaft extending longitudinally of the valve compartment and air chamber, a hollow valve body having a rearwardly extending tubular portion and slideable on the shaft, said valve body having air outlet apertures therein, fluid pressure means for operating the valve body into the open and closed positions, said tubular portion cutting off the admission of air from the air chamber to the valve receiving compartment upon the valve being moved off its seat, a plurality of suitably spaced apart air regulating cones slidably mounted with 75 respect to the valve shaft, the forward cone having a central aperture therethrough and fluid pressure means for operating the cones into the functioning position simultaneously with the closing of each valve, the tubular portion of the valve body moving the cones into their non-functioning position on the opening of the valves. 80

WILLIAM HENRY WHARTON.
